UNITED STATES PATENT OFFICE.

CHARLES S. DEMAREST, OF BROOKLYN, NEW YORK, ASSIGNOR TO AMERICAN TELEPHONE AND TELEGRAPH COMPANY, A CORPORATION OF NEW YORK.

AMPLIFIER FOR RINGING-CURRENTS.

1,322,482.

Specification of Letters Patent. Patented Nov. 18, 1919.

Application filed April 11, 1918. Serial No. 228,007.

To all whom it may concern:

Be it known that I, CHARLES S. DEMAREST, residing at Brooklyn, in the county of Kings and State of New York, have invented certain Improvements in Amplifiers for Ringing-Currents, of which the following is a specification.

This invention relates to transmission lines in which are included repeater elements, and 10 more particularly to a means for transmitting ringing current over such lines.

It is one of the objects of the invention to provide means for transmitting amplified ringing current through a repeater station 15 included in a transmission line. A further object is to provide means whereby during the ringing operation all the amplified energy is transmitted to the outgoing line. Other and further objects of the invention 20 will be clear from the detailed description to be given later.

The purposes of this invention are accomplished by so modifying a two-way two-repeater circuit that it will function during 25 the transmission of ringing current as a one-way repeater circuit for amplifying ringing current. Switching means responsive to ringing current are so arranged that upon their actuation, the output circuit of 30 the amplifier for repeating in the direction in which the ringing current is transmitted, is disconnected from the usual three-winding transformer of the other amplifier, and is connected to the outgoing line through an 35 auxiliary circuit, the other amplifier being at the same time disconnected from the outgoing line so that it is inoperative. The ringing current is then transmitted from the incoming line through the amplifier directly to the outgoing line and no energy is 40 wasted in the balancing artificial lines.

This invention may now be more fully understood from the following detailed description taken in connection with the accompanying drawings, in the Figures 1 and 2 of which when taken together is illustrated a preferred form of the circuit arrangement of my invention. The characters 45 L_1 and L_2 represent incoming and outgoing transmission lines associated with a two-way two-element repeater, which is diagrammatically illustrated as including the repeater elements R_1 and R_2 . The repeater elements are herein illustrated as of the 50 vacuum tube type, although any other well-

known type, such as the mechanical repeater, may be employed. Associated with the repeater elements R_1 and R_2 are the artificial lines N_1 and N_2 , which are adapted to balance the sections L_1 and L_2 , respectively, 60 of the transmission line. Bridged from the mid-points of the input windings of the repeaters R_1 and R_2 are the relays 2 and 5, respectively. These relays are adapted to be energized by the ringing current coming 65 in over the sections L_1 and L_2 of the transmission line. Under the control of these relays are additional normally energized relays 10 and 11. The deenergization of relay 10 serves to operate relays 3 and 6. The de- 70 energization of relay 11 serves to operate relays 4 and 1. The operation of relays 3 and 4 serves to open the outgoing talking circuits of the repeaters and allows the amplified ringing current to be transmitted directly from the repeaters to the transformer. 75 Transformer 7 is designed to be highly efficient for the particular frequency of the ringing current employed, and which in practice may be in the neighborhood of 133 80 cycles. The operation of relays 1 and 6 serves to connect the sections L_1 and L_2 of the transmission line to an auxiliary circuit comprising conductors 8 and 9 which lead to the transformer 7. By these means the 85 amplified ringing current may be transmitted out over either the line L_1 or L_2 . The operation of relays 3 and 4 also serves to open the circuits including the artificial lines N_1 and N_2 , respectively, so that none 90 of the energy of the incoming ringing current will be wasted thereover.

Further details of the invention will now be clear from the following description of its operation: The ringing current in coming over the line L_1 will pass through the windings 22 and 23 and over conductors 26 and 27, and thence through the right-hand winding of transformer 32. A portion of this ringing current will also pass through 100 the winding of the relay 2 and cause it to operate. The operation of relay 2 causes it to pull up its armature and break the following normally closed circuit through relay 10: from ground and battery, winding 105 of relay 10, conductor 31, armature of relay 2 to ground. This will deenergize relay 10 and allow its armature to fall off and close the following circuit: from ground and battery, winding of relay 3, conductor 18, con- 110

tacts of relay 10, conductor 20, and winding of relay 6 to ground. The closing of this last mentioned circuit operates relays 3 and 6. The operation of relay 3 opens the talking circuit of the repeater R_1 and allows the repeated ringing current to pass over conductors 14 and 15, instead of over the talking conductors 36 and 37. This repeated ringing current will then pass over conductors 16 and 17 through one winding of the step-up transformer 7. An induced amplified ringing current will then be transmitted from the other winding of transformer 7 over conductors 8 and 9 to the armatures of relay 6. As has been formerly pointed out, the relay 6 was energized, and accordingly this ringing current will be transmitted from the armatures of relay 6 over the line section L_2 .

20 Ringing current in coming over section L_2 of the transmission line will be transmitted through the windings 24 and 25 and over the conductors 28 and 29 and the winding of transformer 33. A portion of this current will pass through the relay 5 and operate said relay. The operation of relay 5 will break the normally closed circuit through relay 11, which will allow its armature to fall off and close a circuit from ground and 30 battery, winding of relay 4, conductor 19, contacts of relay 11, conductor 21, and winding of relay 1 to ground. The closing of this last mentioned circuit operates relay 4 and relay 1. Upon the operation of relay 4 the talking conductors 38 and 39 are disconnected from the repeater R_2 and amplified ringing current will pass over the conductors 34 and 35 instead of over the talking conductors 38 and 39. This repeated ringing current will then pass over conductors 16 and 17 and through one winding of the transformer 7, and induced amplified ringing current will then be transmitted from the other winding over conductors 8 and 9 to the armatures of relay 1. As this relay has already been energized, it will be seen that ringing current will be transmitted over the armatures of relay 1, and over the section L_1 of the transmission line.

40 It will be obvious that the general principles herein disclosed may be embodied in many organizations other than those illustrated without departing from the spirit of the invention, as defined in the following 55 claims.

I claim:

1. In a transmission system comprising two line sections, a two-way two-repeater organization interconnecting said line sections for the transmission of talking currents, said repeater organization including artificial lines for balancing said line sections and two-repeater elements, each repeater element having its input circuit associated with one of said line sections, and

having its output circuit associated with the other line section and the corresponding artificial line in such manner that substantially half of the output energy is transmitted to the artificial line, and means directly responsive to ringing current transmitted over one line section to disconnect the output circuit of the repeater element associated with said section from the other line section and artificial line, and connecting the output circuit to the outgoing line only. 70

2. In a transmission system comprising two line sections, a two-way two-repeater organization interconnecting said line sections for the transmission of talking currents, said repeater organization including artificial lines for balancing said line sections and two-repeater elements each repeater element having its input circuit associated with one of said line sections, and 80 having its output circuit associated with the other line section and the corresponding artificial line in such manner that substantially half of the output energy is transmitted to the artificial line, and means directly responsive to ringing current transmitted over one line section to disconnect the output circuit of the repeater element associated with said section from the other line section and artificial line, and connecting the output circuit to the outgoing line only, 85 whereby ringing current transmitted over one line section is amplified by the repeater element and directly transmitted to the other line section. 90

3. In a transmission system comprising two line sections, a two-way two-repeater organization interconnecting said line sections for the transmission of talking currents, said repeater organization including 105 artificial lines for balancing said line sections and two-repeater elements each repeater element having its input circuit associated with one of said line sections, and having its output circuit associated with the 110 other line section and the corresponding artificial line in such manner that substantially half of the output energy is transmitted to the artificial line, an auxiliary circuit to which either line section may be connected, 115 and means for connecting the output of the repeater element associated with one of said line sections to said auxiliary circuit and for simultaneously connecting said auxiliary circuit to the other line section. 120

4. In a transmission system comprising two line sections, a two-way two-repeater organization interconnecting said line sections for the transmission of talking currents, said repeater organization including 125 artificial lines for balancing said line sections and two-repeater elements, each repeater element having its input circuit associated with one of said line sections and having its output circuit associated with the 130

other line section and the corresponding artificial line in such manner that substantially half of the output energy is transmitted to the artificial line, means directly responsive to ringing current transmitted over one line section to disconnect the output circuit of the repeater element associated with said section from the other line section and artificial line and connecting the output circuit to the outgoing line only, and means controlled by said directly responsive means to disconnect the artificial line from the line section over which the ringing current is transmitted.

5. In a transmission system comprising two line sections, a two-way two-repeater organization interconnecting said line sections for the transmission of talking currents, said repeater organization including artificial lines for balancing said line section and two-repeater elements, each repeater element having its input circuit associated with one of said line sections and having its output circuit associated with the other line section and the corresponding artificial line in such manner that substantially half of the output energy is transmitted to the artificial line, and means responsive to the ringing current transmitted over one line section to disconnect the artificial line associated with said line section

10

15

20

so that none of the ringing current is diverted through the artificial line.

6. In a transmission system comprising two line sections, a two-way two-repeater organization interconnecting said line sections for the transmission of talking currents, said repeater organization including artificial lines for balancing said line sections and two-repeater elements, each repeater element having its input circuit associated with one of said line sections, and having its output circuit associated with the other line section and the corresponding artificial line in such manner that substantially half of the output energy is transmitted to the artificial line, an auxiliary circuit to which either line section may be connected, said auxiliary circuit including a transformer adapted to be highly efficient for the transmission of currents having a frequency of the order of the currents employed for ringing purposes, and means for connecting the output of the repeater element associated with one of said line sections to said auxiliary circuit and for simultaneously connecting said auxiliary circuit to the other line section.
